UNITED STATES PATENT OFFICE

2,545,348

CATHODE-RAY TUBE SUPPORT

George W. Fabel, Fulton, N. Y., assignor to General Electric Company, a corporation of New York

Application January 13, 1950, Serial No. 138,487

6 Claims. (Cl. 177—316)

1

My invention relates generally to cathode ray tubes and, more particularly, to means for supporting cathode ray tubes within the cabinet of a television receiver. While my invention is of general utility, it is particularly suitable for use in television receivers which employ a cathode ray tube having a metal cone which is operated at a relatively high potential.

Certain types of cathode ray tubes recently placed on the market have employed a metal cone which is secured to the glass face plate of the cathode ray tube by a suitable glass-to-metal seal. Since the inner surface of the cone is used as the accelerating anode for the cathode ray tube and the cone is conductive, the entire metal cone is operated at the relative high potential necessary for the accelerating anode. In many instances this accelerating potential may be of the order of 15,000 volts or higher. In mounting such a cathode ray tube in the cabinet of a television receiver, great difficulty is experienced in reducing leakage from the highly charged metal cone to the surrounding portions of the cabinet. Also, in mounting such cathode ray tubes, means must be provided to prevent corona discharge from the metal cone to surrounding objects at ground potential. Additionally, the supporting means must provide a good mechanical support for the cathode ray tube which is generally of relatively large diameter. Accordingly, it is a primary object of my invention to provide a new and improved support for the cathode ray tube of a television receiver.

It is a further object of my invention to provide a new and improved mounting means for a cathode ray tube of the metal cone type which is particularly suitable for use in television receivers, and which is of simple construction and low cost.

It is another object of my invention to provide a new and improved support for cathode ray tubes of the metal cone type wherein corona discharge to points of ground potential is substantially eliminated.

It is still another object of my invention to provide a new and improved support for a cathode ray tube of large diameter wherein the cathode ray tube is rigidly supported within the cabinet of a television receiver.

It is a still further object of my invention to provide a support for a cathode ray tube of the metal cone type wherein leakage from the metal cone of the cathode ray tube to the cabinet of the receiver is minimized.

The features of my invention which I believe

2

to be novel are set forth with particularity in the appended claims. My invention itself, however, both as to its organization and method of operation, together with further objects and advantages thereof, may best be understood by reference to the following description taken in connection with the accompanying drawing, in which Fig. 1 is a side elevational view partly in section of a cathode ray tube support employing the principles of my invention, Fig. 2 is a rear elevational view of the structure of Fig. 1 taken along the line 2—2 thereof, and Fig. 3 is a cross-sectional view of a portion of Fig. 2 taken along the lines 3—3 thereof.

15 Referring now more particularly to the drawing, I have illustrated therein a television cabinet indicated generally at 1 within which is mounted a cathode ray tube indicated generally at 2. The cabinet 1 is provided with a transparent safety plate 3 behind which is positioned a mask 4. The mask 4, which may be of any suitable material such as rubber or the like, is provided with an aperture which defines the viewing area of the cathode ray tube. The cathode ray tube is provided with a metal cone 5 and a curved transparent face plate 6 which is secured to the base of the cone 5 by a suitable glass-to-metal seal. The cabinet 1 is provided with a top member 10 and a front panel member 11. The safety plate 3 may be secured to the front panel 11 by any convenient means such as the thumb screw 12, or the like.

In order to mount the cathode ray tube 2 within the cabinet 1 in a manner substantially to prevent leakage to the cabinet and corona discharge from the metallic cone of the cathode ray tube, I provide a pair of support members 15, 16 which extend substantially vertically within the cabinet 1. The support members 15, 16 are supported at their extreme ends within the cabinet and spaced somewhat behind the front panel 11. The support members 15, 16 are preferably constructed of a suitable insulating material such as a polystyrene or the like having a relatively high dielectric constant so as to reduce leakage from the cathode ray tube to the cabinet of the receiver. Thus, for example, the upper end of support member 16 is secured to a spacing member 17 by means of a suitable screw 18 or the like, so as to space the member 16 somewhat behind the front panel 11. It will be understood that similar spacing blocks (not shown) are provided to support the other ends of support members 15, 16 so that these members are positioned in spaced, parallel relation to the front panel of the

receiver. In this connection it will be understood that the problems of minimizing leakage to the cabinet and suppressing corona discharge are separate and distinct. Leakage results from a relatively low resistance path between the highly charged cone and ground potential which causes a flow of leakage current which presses a load upon the high voltage power supply. Corona discharge, on the other hand, is an arcing or potential breakdown in air, which occurs at points of highly concentrated potential such as exist at sharp points and the like.

In order that the cathode ray tube may be supported in approximately the correct position for viewing through the aperture of the mask 4, I prefer to make the support members 15, 16 of right angle construction, one arm of the right angle serving as a support for the rim of the cathode ray tube and the other arm of the right angle acting as a centering means therefor. Thus, referring to Fig. 2 wherein the relative positioning of these members is clearly illustrated, the support members 15, 16 which are supported from the cabinet at the extreme ends thereof, contact the cathode ray tube cone at the points 19 and 20. One arm 31 of the support member 15 acts as a support against which the rim of the cathode ray tube cone may be held. The other arm 32 of the support member 15, which arm extends perpendicularly to arm 31, prevents the cathode ray tube rim from moving sideways thereby positioning the face of the cathode ray tube for proper viewing of the screen thereof. As is well illustrated in Fig. 2, the supporting members 15, 16 contact the rim of the cathode ray tube for a relatively short distance along the length thereof and a substantial leakage path is provided from the supported end of each support member to the points of contact with the metal rim of the cathode ray tube. In order to reduce corona discharge from the highly charged metal cone to points on the support members 15, 16, I provide all corners of the right angle support members with a substantial radius so that the electric field distribution between the cone and the corners of the right angles does not become so concentrated as to cause breakdown therebetween.

The support members 15, 16 are spaced from the front panel of the receiver by an amount just sufficient to enable the face plate 6 of the cathode ray tube to be positioned adjacent the rear face of the mask 4. By such an arrangement, the leakage path for the cathode ray tube is through air to all parts of the cabinet except through the relatively long leakage paths provided by the support members 15, 16.

In order securely to hold the rim of the cathode ray tube against the right angle support members 15, 16, I provide a pair of elongated cross members 21, 41, which are positioned transversely of the axis of the metal cone 5 and are adapted to engage the sloping surfaces of the cone at oppositely spaced points thereon. The cross members 21, 41 are movable back and forth within the cabinet so that they may be moved forward to a point where the central portion of the cross members engages the surface of the cone and exerts sufficient pressure thereon securely to engage the base of the cone with the center portion of the support members 15, 16.

In order to support the cross members 21, 41 in such a manner that they may be readily moved forward and backward within the cabinet, I provide a plurality of brackets 22, which are secured

to the side panels of the cabinet by any suitable securing means, such as the screws 23, or the like. The brackets 22 are provided with horizontally extending portions 24 which are slotted 5 to receive a bolt 25 and wing nut 26. Suitable openings are provided in the ends of the cross members 41, 21 so as to receive the bolts 25. The cross members 41, 21 may conveniently be made of suitable hardwood doweling in which case sections of tubing 30 are placed over the cross members 41, 21 for a substantial portion of the length thereof. The tubing 30 is preferably constructed of a suitable insulating material having a high dielectric constant so as to provide 10 adequate leakage paths back to the cabinet wall.

Fig. 2 clearly illustrates the relative positioning of the metallic cone 5 of the cathode ray tube and the cross members 41, 21. It is evident from this figure that the cross members 41, 21 contact 15 the sloping surface of the cone at a point intermediate the ends thereof, and that a substantial leakage path is provided from the point of contact of the metal cone to the sides of the cabinet.

In operation, a cathode ray tube is first placed 20 within the arms 32 of the support members 15, 16 and held against the arms 31 of these support members with the face plate of the cathode ray tube in correct position for viewing a reproduced picture. The cross members 41, 21 are then 25 moved forward towards the front panel so as to clamp the metal cone of the cathode ray tube between the support members 15, 16 and the cross members 41, 21. By such an arrangement, 30 the cathode ray tube is securely held in position for viewing through an aperture in the front panel of the receiver and substantial leakage paths are provided from all points of the metal cone of the cathode ray tube to the surrounding cabinet structure. By providing elongated cross 35 members having curved surfaces at the point of engagement with the metal cone, a radius to radius contact is made between the cross members and the metal cone which operates substantially to reduce corona discharge from the highly charged cone 5 to the supporting rods 41, 21. Also, due to the fact that the support members 15, 16 contact only the front rim of the cathode ray tube and then only for a relatively 40 short distance along the rim on each side, leakage from the highly charged metal cone to the cabinet is substantially prevented.

In Fig. 3 there is illustrated more clearly the 45 relative positioning of the metal rim of the cathode ray tube and the right angle support members 15, 16 at the points of contact therebetween. In Fig. 3 it is seen that the metal cone 5 terminates in a rim portion 45 which conforms to the inner surface of the upper arm 32 of the right angle support and is provided with a curved portion 46 which contacts the lower arm 31 of the right angle support. This figure also illustrates that the corners 47 of the right angle support members are provided with a relatively large 50 radius to reduce corona discharge between the cone and the right angle support members.

From the foregoing, it is evident that the present invention provides a supporting means for a cathode ray tube of the metal cone type in which substantial leakage paths are provided to all 55 points of the cabinet although the face plate of the cathode ray tube is mounted substantially adjacent the front panel of the receiver. In addition, corona discharge from the highly charged metal cone of the cathode ray tube is substan-

tially prevented by providing radius to radius contacts between the supporting members and the metal cone.

While the invention has been described by reference to particular embodiments thereof, it will be understood that numerous modifications may be made by those skilled in the art without departing from the invention. I therefore aim in the appended claims to cover all such equivalent variations as come within the true spirit and scope of my invention.

What I claim as new and desire to secure by Letters Patent of the United States is:

1. In a television receiver of the type employing a cathode ray tube adapted for viewing the screen thereof through an aperture in the front panel of the cabinet of the receiver, said cathode ray tube having a metal cone adapted to be energized to a high potential, means for mounting said cathode ray tube while substantially preventing corona discharge to said cabinet comprising, a first pair of support members engaging the rim of said cone at diametrically opposed points thereon, the ends of said support members being supported within said cabinet so as to permit viewing of the screen of the cathode ray tube through said aperture, and a pair of rod-like cross members positioned to engage the sloping surface of said metal cone at diametrically opposed points along a periphery of somewhat smaller diameter than the maximum diameter of said cone, and means for moving the ends of said cross members towards said support members thereby securely to clamp said cone between said support members and said cross members.

2. Means for mounting a cathode ray tube of the metal cone type within the cabinet of a television receiver comprising, a plurality of insulated support members adapted to engage the rim of said cone and having a relatively long leakage path to said cabinet, said support members being positioned within said cabinet so as to permit viewing of said cathode ray tube through an aperture in said cabinet, and a plurality of rod-like cross members positioned transversely of the axis of said cone and adapted to engage the sloping surface of said cone at spaced points thereon, and means for supporting said cross members from said cabinet with the curved surface thereof in engagement with said cone thereby securely to clamp said cone between said supporting members and said cross members.

3. Means for mounting a cathode ray tube of the metal cone type within the cabinet of a television receiver comprising, a plurality of insulated support members adapted to engage the rim of said cone and having a relatively long leakage path to said cabinet, said support members being positioned within said cabinet so as to permit viewing of said cathode ray tube through an aperture in said cabinet, and a plurality of rod-like cross members positioned transversely of the axis of said cone and adapted to engage the sloping surface of said cone at spaced points thereon, and means for supporting said cross members from said cabinet with the curved surface thereof in engagement with said cone thereby securely to clamp said cone between said supporting members and said cross members, said cross members having a relatively long leakage path from the point of contact with said cone to said cabinet.

4. Means for mounting a cathode ray tube of the metal cone type within the cabinet of a television receiver comprising, means for supporting the rim of said cone in a position to permit viewing the screen of said cathode ray tube through an aperture in said cabinet, said supporting means being constructed to restrain said cone against axial movement toward said aperture, and a plurality of elongated cross members adapted to engage the sloping surface of said cone at spaced points on said cone remote from the rim thereof, and means for supporting the ends of said cross members from said cabinet with the intermediate portion thereof in engagement with said cone thereby securely to clamp said cone between said rim supporting means and said cross members.

5. Means for mounting a cathode ray tube of the metal cone type within the cabinet of a television receiver comprising, means for supporting the rim of said cone in a position to permit viewing the screen of said cathode ray tube through an aperture in said cabinet, said supporting means being constructed to restrain said cone against axial movement toward said aperture, and a plurality of elongated cross members adapted to engage the sloping surface of said cone at spaced points on said cone remote from the rim thereof, each of said cross members having a curved surface at the point of contact with said cone thereby substantially to reduce corona discharge between said cone and said cross members, and means for supporting the ends of said cross members from said cabinet with the intermediate portion thereof in engagement with said cone thereby securely to clamp said cone between said rim supporting means and said cross members.

6. Means for mounting a cathode ray tube of the metal cone type within the cabinet of a television receiver comprising, means for supporting the rim of said cone in a position to permit viewing the screen of said cathode ray tube through an aperture in said cabinet, said supporting means being constructed to restrain said cone against axial movement toward said aperture, and a plurality of elongated cross members adapted to engage the sloping surface of said cone at spaced points on said cone remote from the rim thereof, each of said cross members having a curved surface at the point of contact with said cone thereby substantially to suppress corona discharge from said cone to said cross members, and means for supporting the ends of said cross members from said cabinet with the intermediate portion thereof in engagement with said cone thereby securely to clamp said cone between said rim supporting means and said cross members, said cross members having a relatively long leakage path from the point of contact with said cone to said cabinet.
